UNITED STATES PATENT OFFICE.

CHARLES HILAIRE HENRI RODANET, OF PARIS, FRANCE, ASSIGNOR TO SOCIÉTÉ ANONYME: ÉTABLISSEMENTS ED. JAEGER, OF PARIS, FRANCE.

REGISTERING COUNTER.

Application filed January 4, 1924. Serial No. 684,425.

To all whom it may concern:

Be it known that I, CHARLES HILAIRE HENRI RODANET, a citizen of the French Republic, residing at Paris, France, have invented new and useful Improvements in Registering Counters, of which the following is the specification.

It has already been proposed to devise registering revolution counters in which the drums carrying the digits are mounted with slight friction on the driving shaft actuated by the mechanism the number of revolutions of which is to be evaluated and registered. Normally, the drums are immobilized owing to their engagement with a system of abutments, these abutments being withdrawn for allowing the shaft to actuate the drums each time a new unit, ten, etc., must be registered. These mechanisms do not allow, however, to easily effect the setting back to zero and usually it is first necessary to align the drums at the digit nine and then, by means of another operation, to definitively bring them back to zero.

The present invention has for its object improvements in the construction of registering counters of the above mentioned type, these improvements being more particularly adapted to mechanically obtain the setting back to zero of the drums of the register (and optionally that of the totalizer) when the apparatus is provided with a totalizer. In these conditions, it is possible to effect the trials of the counter and to align the drums at zero condition which, actually, cannot be practically obtained with the existing apparatus. These improvements are more particularly characterized in that the digit drums, which are mounted with slight friction on the driving shaft and which tend to be rotated by friction surfaces rigid with the latter, are provided, on one of their side faces, with a ratchet having ten teeth, whilst the other face has only one tooth; an abutment member, constituted by a ring, which is interposed between the contiguous drums and has a transverse pin combining with their respective teeth, acting, in combination with the ratchet having ten teeth, for immobilizing the corresponding drum; the release of the latter and its actuation by the shaft being obtained when the pin of the ring, lifted by the single

tooth of the drum, releases the ratchet having ten teeth belonging to the following drum which registers the units of higher order.

The improvements are also characterized in that, owing to the above mentioned means, it is possible to automatically set back to zero all the digit drums. This result is obtained by actuating the driving shaft in reverse direction to its direction of normal rotation so that the pins of the abutment rings may be disengaged from the ratchets having ten teeth, but, on the contrary, lock themselves on the flank, of the single corresponding tooth, directed in reverse direction to the teeth of the ratchet; this locking corresponds to the stoppage of the drum in the position zero. The invention also relates to a means which allows to obtain, owing to a single driving member, first the separation between the driving shaft and the mechanism which normally actuates it, then the rotation of the said shaft in reverse direction to the normal direction of rotation.

In the accompanying drawings and by way of example:

Figs. 1 and 2 are top and underside perspective views of a totalizing registering counter devised.

Fig. 3 illustrates the two side faces of a digit drum.

Figs. 4 and 5 show the abutment of the drum and one of the friction discs respectively.

Figs. 6 and 7 illustrate respectively the two corresponding faces of two contiguous drums in inoperative period.

Figs. 8 and 9 are corresponding views at the time of the transfer of a unit from one of the drums to the contiguous one representing units of immediately higher order.

Although the description which will follow applies to a registering counter with a totalizer, it is obvious that the means, forming the subject-matter of the invention, would also apply to a counter which is not provided with a totalizer. Moreover, the fitting up of the digit drums and the method of operation are the same for both registering mechanisms.

Essentially, the digit drums 1 carry on one of their side faces a ratchet 2 having ten teeth and on the other face a circular race

3 having a single tooth 4 (Fig. 3). This tooth 4, in the example shown, corresponds to the digit 6, but this obviously results only from constructional considerations and it 5 might correspond to any other indication of the drum. It is however necessary that it should exactly correspond to one of the teeth 10 of the ratchet 2 provided on the other face; the inclinations being directed in reverse direction, as shown in Fig. 3.

The drums 1 are mounted side by side on the driving shaft 5 so that one of the faces carrying the ten teeth ratchet 2 of a drum is arranged against the face of the contiguous 15 drum carrying the single tooth 4. Between the hubs of the drums are interposed friction discs 6 (Fig. 5) having a V-shaped heel piece 7 which fits in a longitudinal groove, of corresponding cross section, of 20 shaft 5. Concentric with this disc 6, is arranged a ring 9 (Fig. 4) the faces of which 25 rub on ratchets of the drums 1. This ring 9 carries a transverse pin 10 which can simultaneously engage with the teeth of the corresponding drums. It is provided with a 30 tail piece 11 which can rock about an axis 14 about which all the rings 9 are thus pivoted. Springs 12 are attached, on the one hand, to the tail pieces 11, and, on the other hand, to another fixed axis 13 (Fig. 2).

The operation of the transfer of the units is the following:

The driving shaft 5 receives its movement from the exterior and rotates in a continuous 35 manner, but the drums 1 are stopped since the pins 10 of the rings 9, under the action of the springs 12, fit between the teeth 2 of the ten teeth ratchet provided on the said drums. If we consider one of the 40 drums, it will be seen that, at the time the latter reaches the digit 9 and at the time where, consequently, the transfer must be effected (that is to say the advance to the extent of one digit of the adjacent drum 45 representing the units of higher order) the single tooth 4 of the drum considered comes in contact with the pin 10 carried by the corresponding ring 9. While the drum considered reaches the zero, the pin 10 passes 50 therefore beyond the tooth 4 (Fig. 8) and simultaneously moves away from the teeth of the ten teeth ratchet 2 provided on the drum of the higher units (Fig. 9).

The latter becoming free is driven by the driving shaft 5 owing to the friction exerted between the disc 6 and the corresponding face of the hub of the drum. When the drums have terminated their tenth of a revolution, the tooth 4 moves away from the 55 pin 10 of the ring 9 which automatically falls back, under the action of its spring 12 (Fig. 6).

The pin 10 comes again in engagement with the ten teeth ratchet 2 and stops the actuating movement of the drum which has

thus registered a unit (Fig. 7). The same action is repeated when the first drum considered has again effected a revolution.

In the example illustrated, the register and the totalizer are devised in a similar 70 manner and are arranged on parallel driving shafts 5.

The actuation of the counter is effected, as illustrated, by the worm 15 which receives the external drive and actuates the wheel 16. 75 This wheel 16 drives a disc having only one tooth as the drums 1 and by means of a ring, such as 9, drives the first drum to the extent of one division at each complete revolution of the wheel 16 and of the corresponding 80 cam-disc. The other drums are arranged and operate as above described. A spring placed at the shaft end takes a bearing on the frame and holds the drums 1 pressed against each other. 85

An intermediate pinion 18 allows to transmit the movement from the wheel 16 to the wheel 19 which actuates the register.

The first drum of the latter is constantly driven by friction and its single tooth 4 combines with a ring 9 interposed between it and the following drum so as to act as described for the transfer. The single tooth 4 of the last drum combines with a circular disc 20 mounted on the shaft and on the ledge of 95 which slides the pin 10 of the ring 9 adapted to constitute a stop for the setting back to zero.

A spring, also arranged at the shaft end holds the drums against each other. 100

For the setting back to zero, a particular control has been provided which allows to break the connection existing between the shaft of the totalizer (that is to say between the external driving system) and the shaft 105 of the register; this control being moreover so devised that it is possible to automatically bring back the drums of the register to zero.

For that purpose, the shaft 21 which carries the intermediate pinion 18 can be longitudinally moved against the action of clutch spring 22. This result is obtained by angularly moving a pivoting square an arm 23 of which forms an incline for exerting a thrust upon the end of the shaft 21. A 110 spring 24 acts on the square so as to tend to disengage the shaft 21. The other arm of this pivoting member forms a paddle or blade 25. The latter is placed under a vertical shaft 26 provided with an operating knob 27 and capable of receiving longitudinal displacements and rotations about its axis. This shaft 26 carries a pinion 28 which can gear with another pinion 29, mounted on the driving shaft 5 of the drums 115 1 of the register. 120

Normally, the spring 24 acts upon the pivoting square for disengaging the shaft 21, so that the intermediate pinion 18 can gear with the pinions 16—19 of the two 130

- shafts driving the drums 1. Simultaneously, the vertical shaft 26 is lifted and its pinion 28 is held out of engagement with the pinion 29 of the driving shaft.
- 5 For the setting back to zero, it suffices therefore to push on the milled knob 27 and to cause it to rotate. The translation releases the intermediate pinion 18 by pushing back the rocking square and the shaft 10 21 and by throwing the pinions 28-29 in gear; the rotation permits to actuate the driving shaft. The drums 1 which are driven by friction in reverse direction to their normal displacement automatically 15 stop by the abutting of the flank of their single tooth 4 against the pin 10 of the corresponding ring 9; the ten teeth ratchets 2 rotating in reverse direction to their normal rotation do not prevent this displacement.
- 20 It is therefore possible with one hand only, without fumbling, and even in the dark to set back the register to zero.
- For the totalizer, no control is provided for the setting back to zero, as this is practically unnecessary. The setting back to zero of the totalizer is effected without taking the mechanism to pieces by actuating each disc separately by movement of pressure and rotation on the edge.
- 30 What I claim as my invention and desire to secure by Letters Patent is:
1. In a registering counter, juxtaposed digit drums adapted to be frictionally operated, a ratchet on one of the drums, the other drums being provided with a circular race, a tooth projecting from said circular race, and means for cooperating with said circular race and said projecting tooth to engage or release the teeth of the ratchet 35 of said digit drum.
  2. In a registering counter, juxtaposed digit drums adapted to be frictionally operated, a ratchet on one of the drums, the other drums being provided with a circular race, a tooth projecting from said circular race, rings engaging freely between the circular race of one of the digit drums and the ratchet of the adjacent digit drum, a pin traversing each of said rings to cooperate at its ends on the one hand with the circular race and the tooth of the drum, and on the other hand with the teeth of the ratchet of the adjacent drum.
- 50 3. In a registering counter, juxtaposed digit drums adapted to be frictionally operated, a ratchet on one of the drums the other drums being provided with a circular race, a tooth projecting from said circular race, rings engaging freely between the circular race of one of the digit drums and the ratchet of the adjacent digit drum, a pin traversing each of said rings to cooperate at its ends on the one hand with the circular race and the tooth of the drum and on the other hand with the teeth of the ratchet of the adjacent drum, and means to permit said rings to move resilient with respect to the circular path of the corresponding digit drum.
- 55 4. In a registering counter, juxtaposed digit drums adapted to be frictionally operated, a ratchet on one of the drums, the other drums being provided with a circular race, a tooth projecting from said circular race, rings engaging freely between the circular race of one of the digit drums and the ratchet of the adjacent digit drum, a pin traversing each of said rings to cooperate at its ends on the one hand with the circular race and the tooth of the drum and on the other hand with the teeth of the ratchet of the adjacent drum, apertured extensions integral with each of said rings, an axis traversing the extensions to permit them to move angularly, springs engaged in the apertures of the rings, and an axis parallel to the oscillating axis of the rings to effect the fixation of the other ends of the springs.
- 60 65 70 75 80 85 In testimony whereof I have signed my name to this specification.

CHARLES HILAIRE HENRI RODANET.
